UNITED STATES PATENT OFFICE.

PERRY J. MYERS, OF COFFEYVILLE, KANSAS.

SECTIONAL-DOOR CONSTRUCTION.

1,366,823.

Specification of Letters Patent. Patented Jan. 25, 1921.

Application filed July 14, 1920. Serial No. 396,067.

To all whom it may concern:

Be it known that I, PERRY J. MYERS, a citizen of the United States, residing at Coffeyville, in the county of Montgomery and State of Kansas, have invented certain new and useful Improvements in Sectional-Door Construction, of which the following is a specification.

The invention relates to a sectional door construction and more particularly to the class of grain car doors.

The primary object of the invention is the provision of a door of this character wherein the same is formed in a plurality of sections 15 adapted to be supported for movement selectively whereby the doorway with which the door is associated can be fully or partly opened or closed and when the sections are moved to open position they will be suspended overhead yet the same may be readily accessible for the closing of the doorway.

Another object of the invention is the provision of a door of this character wherein in the hangers for the sections thereof are 25 of novel form and connected with a doorway in a novel manner so as to permit easy and convenient shifting of the sections of the door for the opening and closing thereof, and said door when in a closed position will 30 constitute a tight closure so as to prevent the leakage of grain from the railway car or other container for the grain, and by reason of the construction and arrangement the sections can be manipulated without ex- 35 cessive time and labor ordinarily required in the opening and closing of a door structure.

A further object of the invention is the provision of a door of this character wherein 40 in the sections when in closed position can be firmly fastened together without possibility of displacement resultant from vibrations incident to the travel of the car, the door being specially designed for use in 45 grain cars.

A still further object of the invention is the provision of a door of this character wherein the construction thereof renders the same extremely simple, thoroughly reliable, 50 and efficient in purpose, strong, durable and inexpensive to manufacture and install.

With these and other objects in view the invention consists in the features of construction, combination and arrangement of 55 parts as will be hereinafter fully described, illustrated in the accompanying drawings

and pointed out in the claims hereunto appended.

In the accompanying drawings Figure 1 is a fragmentary elevation looking from the outer side of a railway car showing the door construction in accordance with the invention applied and in closed position.

Fig. 2 is a fragmentary vertical transverse sectional view, the sections of the door 65 being shown by full lines in closed positions and several of the sections shown by dotted lines in open position.

Fig. 3 is a fragmentary vertical transverse sectional view showing several of the 70 sections of the door about to be locked in closed position.

Fig. 4 is a view similar to Fig. 3 showing the sections closed and locked.

Fig. 5 is an enlarged sectional view on the 75 line 5—5 of Fig. 1 looking in direction of the arrows.

Similar reference characters indicate corresponding parts throughout the several views in the drawings.

Referring to the drawings in detail A designates a portion of the base or sill and B the vertical stiles of a doorway formed in the side of the body of a railway car. Arranged upon each vertical stile B on the face 85 next to the doorway and extended above the same interiorly of the body of the car beneath the roof thereof is a guide strip, preferably made from an L-shaped beam having its base flange 10 secured in any suitable 90 manner, while the guide flange 11 is at right angles thereto projecting outwardly of the doorway.

Movable relative to the guide strips is a door comprising a plurality of board sections 12 each having fixed to its outer face adjacent to each end a hanger including a rigid strap 13 secured transversely of the section 12 and a pair of spaced hook-like horns 14 and 15 respectively, the horn 15 being disposed at an acute angle to the strap 13 while the horn 14 is at right angles thereto and the bills 16 of these horns engage with the flange 11 of the guide strip so that in this manner the sections 12 of the door 105 are slidably connected to said guide strips whereby the sections can be shifted from the position shown by full lines in Figs. 1 and 2 of the drawings to the positions shown by dotted lines in Fig. 2. It will be clearly apparent that when the sections 12 are shifted to open position as shown by dotted lines in

Fig. 2 the same can be closely nested so as to occupy a minimum or the least possible space when the doorway is open and on the shifting of the sections to closed position as shown in Figs. 1 and 2 the said sections will be superimposed perpendicularly edge to edge relative to each other thereby constituting a tight closure for the doorway.

The angular disposition of the horns 14 and 15 of the hangers enables the side hangers to accommodate themselves to the curvature in the guide strips when the door sections are moved from the perpendicular extent of said strips to the horizontal extent thereof or vice versa.

Mounted on the outer faces of the sections 12 of the door intermediately thereof in vertical alignment are interlocking members 17 and 18 respectively, the member 17 being formed with an off-set keeper end 19, while the member 18 is extended to form a latched end 20 to engage under the keeper end 19 when the adjacent sections of the door have their meeting edges brought together. The member 18 is formed with an open eye 21 while on the keeper end 19 is pivoted a hand operable lever 22 in which is hinged an eccentrically movable link 23 the latter being adapted for detachably engaging in the open eye 21 and on the swinging of the lever downwardly and inwardly in parallelism with the door the adjacent sections 12 thereof will be drawn tightly together and locked and in this manner the said sections of the door are securely held in closed position for closing the doorway in the side of the car.

When it is desired to open any of the sections the lever is swung outwardly and upwardly so that the link can be disengaged from the open eye 21 thereby freeing the adjacent sections from each other and on sliding these sections upwardly on the guide strips to a position overhead interiorly of the car body the doorway will be open and the door when in open position will be out of the way thus avoiding any interference in the filling or emptying of the car.

It is of course understood that the door construction is adaptable for other containers and this is contemplated within the scope of the invention.

From the foregoing it is thought that the construction and manner of operation of the door will be clearly understood and therefore a more extended explanation has been omitted.

What I claim is:

1. In a door of the character described, a plurality of board like sections, angle strips arranged vertically and horizontally at opposite sides of a doorway and having intermediate curved portions joining the vertical and horizontal stretches thereof, hangers secured to said sections and having angular hook portions slidably engaged with the angle strips, one hook of each hanger being of less length than the other hook and disposed angularly relative thereto for permitting the sections to be overlapped when the hangers are moved on to the horizontal portions of the angle strips for the close nesting of said sections.

2. In a door of the character described, a plurality of board like sections, angle strips arranged vertically and horizontally at opposite sides of a doorway and having intermediate curved portions joining the vertical and horizontal stretches thereof, hangers secured to said sections and having angular hook portions slidably engaged with the angle strips, one hook of each hanger being of less length than the other hook and disposed angularly relative thereto for permitting the sections to be overlapped when the hangers are moved on to the horizontal portions of the angle strips for the close nesting of said sections, and means carried by the sections for interlocking engagement when said sections are brought to closing position.

3. In a door of the character described, a plurality of board like sections, angle strips arranged vertically and horizontally at opposite sides of a doorway and having intermediate curved portions joining the vertical and horizontal stretches thereof, hangers secured to said sections and having angular hook portions slidably engaged with the angle strips, one hook of each hanger being of less length than the other hook and disposed angularly relative thereto for permitting the sections to be overlapped when the hangers are moved on to the horizontal portions of the angle strips for the close nesting of said sections, means carried by the sections for interlocking engagement when said sections are brought to closing position, and clamps coöperating with said last named means to fasten the sections closed.

In testimony whereof, I affix my signature hereto.

P. J. MYERS.
